[57] **CLAIM**

The ornamental design for a multicompartmentalized

transdermal patch for administering drugs to the skin, as shown and described.

DESCRIPTION

FIG. 1 is a top perspective view of a multicompartmentalized transdermal patch for administering drugs to the skin, showing my new design;

FIG. 2 is a bottom perspective view thereof;

FIG. 3 is a bottom perspective view thereof with the protective layer removed;

FIG. 4 is a bottom plan view thereof;

FIG. 5 is a side view thereof;

FIG. 6 is a top plan view thereof;

FIG. 7 is an end view thereof;

FIG. 8 is a top perspective view of an alternate embodiment of FIG. 1;

FIG. 9 is a bottom perspective view thereof;

FIG. 10 is a bottom perspective view thereof, with the protective layer removed;

FIG. 11 is a bottom plan view thereof;

FIG. 12 is a side view thereof;

FIG. 13 is a top plan view thereof;

FIG. 14 is an end view thereof;

FIG. 15 is a top perspective view of another alternate embodiment of FIG. 1;

FIG. 16 is a bottom perspective view thereof;

FIG. 17 is a bottom perspective view thereof, with the protective layer removed;

FIG. 18 is a bottom plan view thereof;

FIG. 19 is a side view thereof;

FIG. 20 is a top plan view thereof; and

FIG. 21 is an end view thereof.
